STARTER DEVICE FOR INTERNAL-COMBUSTION ENGINES

Albert Callsen, Stuttgart-Botnang, and Adolf Weiss, Marbach-on-the-Neckar, Germany; vested in the Alien Property Custodian

Application November 4, 1940, Serial No. 364,272.
In Germany October 20, 1939.

15 Claims. (Cl. 74—6)

This invention relates to starter devices for internal combustion engines, of the type in which the driving member, for example, a pinion, is connected with the driving shaft of the starter by a friction clutch having a screwable pressing member and effecting a positive driving connection only after the driving member has come into mesh with the driven member, said driving member being engaged arbitrarily with the driven member, for instance, the toothed rim of the fly wheel of an internal combustion engine, by hand or by a mechanically operating thrust force, such as, an electro-magnet.

In starter devices of the kind referred to, and generally in starters having a pinion to be meshed with a toothed wheel, the teeth of the pinion may happen to come into a face to face position with the teeth of the toothed wheel and it may be locked in this position, it being difficult to release the pinion from such locked position. The most common remedy, which, however, is by no means satisfactory, consists in that the pinion is withdrawn by force, by switching in the starter motor, through the engaging lever, and then thrown into mesh under action of a pressure spring which is loaded by the engaging lever. This, however, involves violent action and therefore is detrimental for the pinion and the toothed wheel, the withdrawal oftentimes being even impossible, if the pinion and the toothed wheel are already damaged.

According to another proposition, the locked pinion and the driving shaft are relatively turned by an axial displacement of one of the two parts of the threaded connection with respect to the other, then repeating the meshing-in operation. This, however, is only possible with small starters for light motors, in view of the forces required for turning the driving shaft.

It is an important object of the present invention to provide a device which does not show the above mentioned drawbacks, can be used for large starter devices and is simple, inexpensive and safe in operation.

With this and further objects in view; as may become apparent from the within disclosures, the invention consists not only in the structures herein pointed out and illustrated by the drawing, but includes further structures coming within the scope of what hereinafter may be claimed.

The character of the invention, however, may be best understood by reference to certain of its structural forms, as illustrated by the accompanying drawing in which—

Fig. 1 is a schematic side elevation, partly in

section, of a starter device having the invention applied thereto.

Fig. 2 is a similar view, showing a modification, and

Fig. 3 is a similar view of a second modification.

As here shown, an important feature of our novel starter device consists in that a pressure member during the throwing-in action is positively connected with a part of the friction disks only, the rest of the friction disks being positively engaged only at the end of the longitudinal motion of the driving member, and a resilient pressure member being interpolated between the driving member and the part which is arbitrarily moved by the driver or operator.

Referring now to the drawing in greater detail, and first to Fig. 1, it will be noted that a shell-shaped clutch member *c* constituting the driving part of a frictional disk clutch *b* of the free-motion type is seated on a driving shaft *a* of the starter device which, for instance, may be driven by an electric motor.

The driven part of the clutch, constituted by a pressure disk *d*, is fixedly keyed on a shaft *f* by means of its hub *e*, frictional disks *g* being interposed between the shell member *c* and the hub *e* of the pressure disk. The last frictional disk *g'* adjacent to the pressure disk *d* is engaged between the pressure disk *d* and a shell or sleeve *h* which surrounds the coupling shell *c* and is slidable thereon, a pressure plate *i* bearing against the coupling member *c* by means of springs *k* and serving as an abutment face for the frictional disks.

The shaft *f* is formed with a thread *m* engaged by a pinion *n*. A pressure spring *o* is inserted between the pinion and the pressure disk *d*. Another spring *q* is arranged between the pressure disk and the casing *p* of the starter.

Slidably mounted on the hub of the coupling member *c* is a sleeve *r* which is engaged by a bifurcated lever *s* and serves for throwing in the pinion. A pressure spring *t* is disposed between the sleeve *r* and the shell *h*.

The device operates as follows: In order to engage the pinion *n* of the starter with the toothed wheel *u* of the internal combustion engine, the driver or operator advances the sleeve *r*, by operation of the lever *s*, thereby moving forward the shaft *f* with its pinion, through spring *t*, shell *h*, friction disk *g'* and pressure disk *d*. Now, in case the teeth of the pinion should strike against the end faces of the teeth of the toothed wheel *u*, thus locking the pinion, the following procedure takes place: The driver

through the friction disk g' and the pressure disk d causes the threaded shaft f to move by a certain length through the locked pinion. Hereby, the pinion is either turned with respect to the toothed wheel, owing to the turning action of the thread or, if the pinion is very tightly locked, the shaft is turned in the thread of the pinion, this being possible owing to the fact that the pressure disk in this state is coupled with the friction disk g' only, permitting transmission of a small torque only. As the driver withdraws the sleeve r , for another engaging attempt, the shaft f with the pinion is moved back by the spring q acting upon the pressure disk d . As soon as the pinion in this movement is released from the teeth of the toothed wheel u , it is moved along the thread m , by the spring o , turned, and simultaneously forced into the space between two teeth. Now the driver may advance the sleeve r once more and engage the pinion completely. One rotation of the driving shaft a the shaft f is at first rotated only under action of the torque transmitted between the pressure disk d and the friction disk g' , screwing itself back in the pinion, which is locked by its engagement with the toothed wheel u of the engine, until the pressure disk d forces all of the friction disks g against the pressure plate i , whereby the entire friction clutch comes to a positive or torque-transmitting engagement. In this operation, the spring t is compressed if the sleeve r is still held in its advanced position by the lever s .

Referring now to the embodiment illustrated in Fig. 2, it will be noted that the pinion shaft 10 is provided with two threads 11 and 12 of similar direction of their pitch. The pinion 13 is seated on the thread 11 while the thread 12 is provided for a pressure nut 14 of the frictional disk clutch. A stop face 15 for the pinion is provided on the front end of the pinion shaft, while a collar 16 for the pressure plate 17 of the clutch is provided on its rear end. Moreover, a stop 18 in the form of a spring or retaining ring for a spring plate 19 is provided on said shaft, between the pinion and the pressure unit, a pressure spring 20 being interpolated between said spring plate 19 and the pinion.

The spring 21 corresponds to the spring q and the shell 22 corresponds to the shell h of Fig. 1. In the embodiment of Fig. 2, the shell 22 is advanced by a push rod 23 extending through the hollow driving shaft 24 of the starter and being operated by hand or, for instance, by an electromagnet (not shown).

The device of Fig. 2 operates as follows: In order to throw the pinion into mesh, the shell 22 is moved, and through the pressure nut 14 and the spring ring 18 moves the pinion shaft with its pinion towards the toothed rim 25 of the engine fly wheel. In case the pinion should get locked at the front face of the toothed rim, the driver advances the shell 22 further, thereby turning the pressure nut 14 as in Fig. 1. As the sleeve 22 is withdrawn for the purpose of a second attempt, the pressure nut with the pinion shaft is moved back by the spring 21 and the pinion is released from its locked position. The released pinion, on the other hand, is advanced on the pinion shaft, by the spring 20 and thereby turned through a certain angle, whereby it is enabled to catch with its respective tooth into the space between two teeth and to mesh on another advance of shell 22 . If the driving shaft is now turned, the pinion at first is screwed on the rotating shaft 10 towards the stop face

15, stopping the shaft as it reaches the stop face. Now the pressure nut is screwed on the stopped shaft, pressing the friction disk against the pressure plate 17 and the collar 16 , whereby the clutch is fully engaged.

Fig. 3 shows an embodiment of our invention which is particularly simple and useful. A driving shaft 30 is formed with a smooth portion 31 and a portion $31a$ having longitudinal grooves or flutes. A pinion 33 having a threaded hub member 32 is supported on the smooth portion to be freely rotatable and slidable, while the pressure nut 34 of a frictional disk clutch is seated on the threaded hub portion 32 . Arranged at both sides of the flange 35 of the pressure nut 34 are frictional disks 36 and 37 which engage into grooves 38 of the shell member 39 of the clutch. The frictional disk 36 is held in position by a spring ring 40 engaged in an inner groove of the shell 39 , which is stepped at its end for formation of a shoulder 41 abutting the frictional disk 37 . The rest of the frictional disks 42 are arranged in customary manner between the shell 39 and the pressure nut 34 . A pressure plate 43 bearing against a stop face 45 on the hub of the pinion, through spring disks 44 , serves as an abutment for the frictional disks. The shell member 39 is slidable on the fluted portion of the driving shaft, but secured against rotation, by engagement with the flutes. A pressure spring 46 in a recessed portion of the shell 39 acts upon a spring washer 47 which engages the hub of the pinion. The stroke of the spring washer 47 in the recess is defined by a spring ring 48 .

The operation of said device is substantially the same as in the case of Figs. 1 and 2. In order to throw the pinion into gear the shell member 39 is advanced and through its shoulder 41 transmits its motion to the frictional disk 37 , the pressure nut 34 and the pinion. In case the pinion in this operation is locked by face to face engagement with the teeth of the toothed rim 49 of the engine fly wheel, the pressure nut is turned on further advance of the shell 39 . On withdrawal of the shell the pinion is released from its locked position and screwed into the pressure nut by the spring 46 , until it meshes into a space between two teeth of the toothed rim of the fly wheel. Now the pinion may be engaged completely by another advance of the shell member 39 . As the driving shaft is rotated, the pressure nut 34 is screwed tight and compresses all of the frictional disks 42 , thus transmitting the full torque to the pinion.

The method and apparatus of the present invention have been described in detail with reference to specific embodiments. It is to be understood, however, that the invention is not limited by such specific reference but is broader in scope and capable of other embodiments than those specifically described and illustrated in the drawing.

We claim:

1. A starter device comprising a driving shaft, a pinion which is freely slidable and rotatable on the driving shaft and formed with a threaded hub portion, a friction clutch including a shell portion, said shell portion being axially slidable on and rotatable with the driving shaft, a nut member seated on said threaded hub portion for longitudinal movement thereof and rotary movement therewith, said friction clutch being operatively connected to said nut member and being controlled by the latter, a friction disk for coopera-

tion with said shell portion and said nut, said disk and nut being arranged to be initially pressed together separately from said clutch and means for axially moving said nut member by said shell portion, through said friction disk, said means also serving to initially press together said disk and nut.

2. A starter device comprising a driving shaft, a pinion which is freely slideable and rotatable on the driving shaft and formed with a threaded hub portion, a friction clutch including a shell portion, said shell portion being axially slideable on and rotatable with the driving shaft, a nut member seated on said threaded hub portion for longitudinal movement thereof and rotary movement therewith, said friction clutch being operatively connected to said nut member and being controlled by the latter, a friction disk for cooperation with said shell portion and said nut, said disk and nut being arranged to be initially pressed together separately from said clutch and means for axially moving said nut member by said shell portion, through said friction disk, said shell portion having an abutment face for said friction disk, said means also serving to initially press together said disk and nut.

3. A starter device comprising a driving shaft, a pinion which is freely slideable and rotatable on the driving shaft and formed with a threaded hub portion, a friction clutch including a shell portion, said shell portion being axially slideable on and rotatable with the driving shaft, a nut member seated on said threaded hub portion for longitudinal movement thereof and rotary movement therewith, said friction clutch being operatively connected to said nut member and being controlled by the latter, a friction disk for cooperation with said shell portion and said nut, said disk and nut being arranged to be initially pressed together separately from said clutch and means for axially moving said nut member by said shell portion, through said friction disk, and a pressure spring engaged between the hub portion of said shell member and the hub portion of the pinion, said means also serving to initially press together said disk and nut.

4. An engine starter device comprising a driving shaft, a driven shaft, a pinion carried by and driven by said driven shaft and adapted to engage a member of the engine to be started, a friction clutch operatively interposed between said driving and driven shafts, said friction clutch including a pressure member carried by said driven shaft, a sleeve member carried by and rotatable with said driving shaft and a series of clutch plates, said plates being operatively connected to said pressure member and said sleeve member respectively, said pressure member being mounted on said driven shaft for longitudinal movement relative thereto and rotary movement therewith and for exerting pressure on all of said clutch plates when said pinion is in driving engagement with the engine, and manually operated means including yielding means cooperating with said sleeve member for moving said pinion into driving engagement with said engine and for exerting pressure on only a portion of said clutch plates.

5. An engine starter device comprising a driving shaft, a driven shaft, a pinion carried by and driven by said driven shaft and adapted to engage a member of the engine to be started, a friction clutch operatively interposed between said driving and driven shafts, said friction clutch including a pressure member carried by said

driven shaft, a sleeve member carried by and rotatable with said driving shaft and a series of clutch plates, said plates being operatively connected to said pressure member and said sleeve member respectively, said pressure member being mounted on said driven shaft and having a screw-threaded connection therewith for exerting pressure on all of said clutch plates when said pinion is in driving engagement with the engine, and means including a resilient member for moving the pinion into driving engagement with the engine and for exerting pressure on only a portion of said clutch plates.

6. A starter device comprising a rotatable driving shaft, a driving member mounted on said shaft for longitudinal movement thereof and rotary movement therewith, a pinion mounted for sliding and rotary movements on said shaft and provided with a threaded hub portion, a nut member mounted on said threaded hub portion for longitudinal movement thereof and rotary movement therewith, a main friction clutch operatively interposed between said driving member and said nut and controlled by the latter, a second low torque-transmitting clutch also interposed between said driving member and said nut and including clutch members arranged to be pressed into operative positions separately from said main clutch, and means for moving said driving member and pinion longitudinally of said driving shaft, said means also operating to initially press upon said low torque-transmitting clutch members.

7. An engine starter device comprising a rotatable driving shaft, a driving member mounted on said shaft for longitudinal movement thereof and rotary movement therewith, a pinion freely mounted on said driven shaft and adapted to engage a member of the engine to be started, said pinion being provided with a laterally extending hub portion, a control member mounted on said hub portion for longitudinal movement thereof and rotary movement therewith, a main friction clutch operatively interposed between said driving member and said control member and controlled by the latter, and a second low torque-transmitting clutch also interposed between said driving member and said control member and including clutch members arranged to be pressed into operative positions separately from said main clutch, said means also operating to initially press upon said low torque-transmitting clutch members.

8. An engine starter device comprising a rotatable driving shaft, a driving member mounted on said shaft for longitudinal movement thereof and rotary movement therewith, a pinion freely mounted on said driving shaft and adapted to engage a member of the engine to be started, said pinion being provided with a laterally extending hub portion, a control member mounted on said hub portion for longitudinal movement thereof and rotary movement therewith, a main friction clutch operatively interposed between said driving member and said control member and controlled by the latter, a second low torque-transmitting clutch, including clutch members, also interposed between said driving member and said control member, and manually operated means including resilient means for compressing the clutch members of said second clutch separately from said main clutch.

9. An engine starter device comprising a rotatable driving shaft, a driving member mounted on said shaft for longitudinal movement thereof

and rotary movement therewith, a pinion freely mounted on said driving shaft and adapted to engage a member of the engine to be started, said pinion being provided with a laterally extending hub portion, a control member mounted on said hub portion for longitudinal movement thereof and rotary movement therewith, a main friction clutch operatively interposed between said driving member and said control member and controlled by the latter, a second low torque-transmitting clutch also interposed between said driving member and said control member and including clutch members arranged to be pressed into operative positions separately from said main clutch, and manually operated means for moving said driving member and pinion longitudinally of said driving shaft, said means also operating to initially press upon said low torque-transmitting clutch members.

10. An engine starter device comprising a driving shaft, a driven shaft adapted to be rotated by said driving shaft and movable longitudinally relative thereto, a pinion carried by said driven shaft and adapted to engage a member of the engine to be started, a friction clutch operatively disposed between said driving and driven shafts, said friction clutch including a pressure member carried by said driven shaft, a second member carried by and rotatable with said driving shaft and a series of clutch plates, said plates being operatively connected to said pressure member and said second member, respectively, said pinion having a threaded connection with said driven shaft whereby it is rotatable therewith and movable longitudinally thereof to cause longitudinal movement of said driven shaft and pressure member and to cause said pressure member to exert pressure on all of said clutch plates when said pinion is in driving engagement with said engine, and means including yielding means for moving said pinion into driving engagement with said engine and for exerting pressure on only a portion of said clutch plates.

11. An engine starter as set out in claim 10 in which the pressure member is rigidly mounted on said driven shaft.

12. An engine started as set out in claim 10 in

which the pressure member has a threaded connection with said driven shaft whereby it is rotatable therewith and movable longitudinally thereof to control the pressure exerted on said clutch plates.

13. An engine starter device for engaging and then rotating a toothed wheel of the engine, comprising a driving shaft, a driven shaft member coaxial with the driving shaft and mounted for longitudinal movement relative to the driving shaft, a pinion member carried by the driven shaft member and movable into mesh with said engine wheel, a free-motion clutch intermediate the driving shaft and driven shaft member, including a plurality of clutch plates, a sleeve member rotatable with the driving shaft and engaging some of said clutch plates and a pressure member carried by the driven shaft member and engaging others of said clutch plates, manually operated means cooperating with said sleeve member and said pressure member for longitudinally moving the driven shaft member and the members carried thereby to bring said pinion member into engagement with said engine wheel, and a coil spring arranged between two of such members in position to be compressed during such longitudinal movement in the event that the teeth of said pinion member strike the end faces of the teeth of said engine wheel, two of said members being interthreaded with each other with said coil spring, when compressed, exerting pressure upon one of the interthreaded members, whereby rotation of one of the interthreaded members is obtained through the force exerted by said compressed coil spring.

14. An engine starter device as recited in claim 13 wherein said spring is also instrumental in exerting pressure on all of said clutch plates when the teeth of said pinion member and engine wheel have properly meshed.

15. An engine starter device as recited in claim 13 wherein said clutch plates are arranged whereby the major portion of them are pressed into operative engagement subsequent to the operation of the remainder of such plates.

ALBERT CALLSEN.
ADOLF WEISS.
